UNITED STATES PATENT OFFICE

93,425

DESIGN FOR A THERMOMETER

Donald F. Sheppard, Blackshear, Ga.

Application June 7, 1934, Serial No. 52,097

Term of patent 3½ years

To all whom it may concern:

Be it known that I, DONALD F. SHEPPARD, a citizen of the United States, residing at Blackshear, in the county of Pierce and State of Georgia, have invented a new, original, and ornamental Design for a Thermometer, of which the following is a specification, reference being had to the accompanying drawing, forming part thereof.

Figure 1 is a view in front elevation of a thermometer, showing my new design.

Figure 2 is a view in side elevation thereof.

Figure 3 is a top plan view.

I claim:—

The ornamental design for a thermometer as shown.

DONALD F. SHEPPARD.
